UNITED STATES PATENT OFFICE.

ADOLPH OTTO URBAN, OF SAN FRANCISCO, CALIFORNIA.

TELEGRAPHIC TRANSLATOR.

1,003,074.

Specification of Letters Patent.

Patented Sept. 12, 1911.

Application filed May 10, 1910. Serial No. 560,433.

To all whom it may concern:

Be it known that I, ADOLPH OTTO URBAN, a subject of the Emperor of Germany, residing in the city and county of San Francisco, State of California, have invented certain new and useful Improvements in Telegraphic Translators, of which the following is a specification.

This invention relates to selective mechanism, known as telegraphic translators, and has for its object the translating of the telegraphic code into characters readily understood by anyone capable of reading. This is done by a series of progressive selections, wherein the selector travels to successive positions in order to select certain bars, making a combination of releases that result in a printed character of type. To accomplish this I employ mechanism shown 20 in the accompanying drawings, in which—

Figure 1, is a plan view of my device, with the cover partly broken away disclosing the mechanism. Fig. 2, is a side view thereof. Fig. 3, is a detail view of the 25 double sliding bar for carrying the type to the printing mechanism. Fig. 4, is a vertical section, showing the selective mechanism, and Fig. 5, is a similar view, showing one key pressed downward also a front 30 view of the printing mechanism.

1 and 2, are two keys representing a dot and dash of the continental telegraph code, respectively, mounted on standards 3 and 4, held normally upward by the springs 5; angle bars 6 and 7, are rigidly attached to the standards 3 and 4, having at their inner ends connecting links 8 and 8'. These links are pivotally attached to radial arms pivotally mounted on the axis of a small gear 10; 40 at their point of connection, with the links 8 and 8', are mounted dogs to engage the teeth of said gears, and move it through the arc of their travel.

The gear 10, is carried by any suitable 45 stationary mounting, and meshes with a rack 11, on the top of the carrier 12. This carrier, has slidably mounted on one side two depressors 13 and 14, normally held in their extreme upward position by springs 50 47, and adapted to depress the horizontal arm of the bell cranks 17, the lower arm of said bell cranks 17, engaging pins 18, on the releasing bars 19 and 20, and causing them to move in a horizontal direction.

55 A number of type bars 21, are suspended from the releasing bars 19 and 20, by small

spring hooks. Mounted on one end of the type bar 21, is a head, carrying on its front face the character to be printed. The lower side 22, of the head is similar in shape to 60 an inverted frustum of a rectangular pyramid, said frustums 22, resting in receptacles or apertures, identical in shape in the carrier bar 23. This bar 23, has a horizontal dove-tailed slide 24, in its outer side, 65 said slide 24, having vertical dove-tailed slides 25, rigidly attached thereto and engaging dove-tailed slots in a stationary piece 26, attached to the casing. Springs 27, hold the slides 25, to their highest position. A handle 55, is attached to one end of the carrier 23. A slot 29 is provided the entire length of the casing and has an upward extension 29' at one end, to provide for the reception of the handle 55, when 70 in its normal position.

A circular disk 30, of any material suitable for the retention of ink, is carried at one end of the casing and is operated by ink rollers 40, 41 and 42, these in turn being 80 operated or rotated by the pawl arm 38 and the ratchet 39, to give an even distribution of the ink.

Between the disk 30 and the strip 32, is a strip of paper 31, which is passed through 85 the feed rollers 33, these, being operated by the contact of the arm 35, and spring pawl 36, carried on one end of the carrier 23 with the ratchet 34. A spring pawl 37, prevents a reverse movement of the feed rollers 33. 90 A box or compartment 43 is used to store the paper strip 31.

Springs 48, in the side of the casing, keep the rack 11, on the selector 12, in mesh with the gear 10.

The continental code is referred to in the following; the bars 19, represent dots and the bars 20, represent dashes. The letters E, T, A, N, I and M, on the top of the type bars 21, represent the characters to be printed 100 and are not the types themselves. If it is desirous of translating the Morse code into the Roman characters of the alphabet which they represent, it is only necessary to proceed as follows. Should the first character be a dot only, (E), then the key 1, which represents a dot, should be depressed. This carries the angle bar 6, downward, and depresses the depressor 13, which in turn operating through the bell crank 17, and pin 110 18, moves the first bar a slight distance, and causes the slot 61, to come under the hook.

The type bar E is then released, all the other openings or notches of the bars 19 and 20 and in line with or beneath the hooks of the "E" bar are of such width or in such position that the hooks of that bar only will pass through them. The frusto-pyramidal stems or members 22 fit loosely within the corresponding sockets of the bar 23 in such a manner that they are carried with the bar 23 in its journey to the printing mechanism provided that they have first been released from the bars 19 or 20 by the proper selection of the operating keys 1 or 2. The arm 44 is an extension secured to and traveling with the arm 23 and is used for the purpose of supporting the other end of the type bar in its journey to and from the printing mechanism, and on return of arm 23 the extension 44 serves to return the outwardly extending portion of the type arm to its place, and by serving as a support, insures the engagement of the hooks on the type arm with the bars 19 and 20. In printing the character of the last type arm at the right of Fig. 1 the handle 55 must be moved in the slot 29 the full length of the machine until the face of the type comes in contact with the printing disk 30. An opening in the opposite end of the casing is shown on Fig. 2 at the lower left hand corner so that the traveling bar 23 may protrude therefrom. After the selected character is printed on the paper strip 31, the bar 23 is returned to the opposite end of the slot 29, then moved upward into the extension 29' of the slot 29 until the hooks of the type bars 21 spring into position above the bars 19 and 20, the extension 44 serving to support the opposite end of the type bar 21 from that supported by the traveling bar 23. When the bell crank lever 17, is depressed, a flat spring 49, exerts a downward pressure on the bar 19 (or 20 when the dash is pressed) at the same time that it is moved horizontally. This causes a slight downward movement of said bar 19, and permits a shoulder 51, to engage the ledge on which that end of the bar 19, is resting. This is to prevent the premature return of the bar through the action of spring 50. The carrier, 23, is now brought down by means of the handle 55, until it rests on the bottom of the casing, then carried in the direction of the printing mechanism in the opposite end of the casing. As it started, it operated the pawl arm 38, ratchet 39, ink rollers 40, 41 and 42, and caused the inking disk 30, to revolve slightly. Continuing, the carrier moves on, until the face 60 of the type bar E, is brought into contact with the disk 30, and the resulting pressure, causes the type E to leave an impression on the paper strip 31. Returning the carrier 23, to the other end of the casing, it is returned to its upward position by the springs 27, on the vertical carrier 25, and

the type bar E is returned to its position, at the same time lifting the bar 19, disengaging the shoulder 51, and allowing the spring 50 to return said bar 19, to its normal position. Should it be desired to translate a dash, (representing the letter T) the same operation will suffice and the same movements are brought into play, with this exception, when key 2 is depressed, it operates the first of the bars 20, instead of the first bar 19, causing the letter T to be printed. 75

Should it be desired to translate a dot and a dash (representing the letter A) the operation is as follows. Press the key 1, which is a dot, and through the mechanism hereinbefore described, the first of bars 19, is moved horizontally, thereby releasing the first hook of the letter E and all other letters whose equivalent in the continental code begins with a dot. The spring 5, returning the key 1, to its normal position, causes the pawl 9, on its return movement to rotate the gear 10, sufficiently to move the selector 12, to a position which will bring both depressors 13 and 14, to the second horizontal bar in each set (19 and 20). Key 2, representing a dash, is now depressed and the same operation takes place, with the exception of the second bar 20, being moved horizontally, which brings a space under the hook on type bar 21, representing A, and moves the space on the same horizontal bar away from the hook on type bar 21, representing E. This releases A and locks E. To return the selector 12, to its normal position, with its depressors 13 and 14 over the first bars in 19 and 20, the square sliding bar 15, on which it is slidably mounted is moved forward against the tension of springs 48, when the tension of spring 16, 100 will return the selector 12, to its normal position against a suitably located stop. By releasing the bar 15, the tension of the springs 48, will return the bar 15, and selector 12, to their proper positions and the rack 11 will mesh with the gear 10. As each key is depressed, one of the pawls 9, serves to prevent the reverse movement of the selector, until it is unmeshed from the gear 10. 105 110 115 120 125 130

In translating combinations of like character but different succession, viz., A, dot dash and N, dash dot, if the dot and dash keys are depressed in the order of the combination, the letter representing that order of succession will be selected and printed and not the other. For instance, the letter A, being represented in the continental code by first a dot and then a dash, the type bar 21, representing A will be released if the dot key 1, is pressed first and the dash key 2, is pressed second, as the pressing and releasing of the dot key moved the selector 12, to its second position so that the dash key 2, being depressed, operated only the second bar of the set marked 20. If the

dash key 2, were depressed first, then one hook of N, would be released, its release being partly on the first bar of 20 (dash), and if dot key 1, were then depressed the second bar 19, of the dot bars would complete the release. In other words the release for A is found in the first bar of the dot set (19) and the second bar of the dash set (20) whereas, the release for N is found in the first bar of the dash set (20) and the second bar of the dot set (19). It will then be seen that by operating either a dot or a dash bar, all letters beginning with that character, are partially released, except E or T, which are wholly released. If a second operation is performed it locks E or T and releases A or N, if a third operation is performed, it locks the release of A or N, and releases other letters beginning with the same combination of characters, in the same order of succession, consisting of three characters, and so on through a number of combinations which is only limited by the number of releasing bars employed.

25 It is obvious from the foregoing, that any combination of dots and dashes may be translated into letters and figures.

While the continental code has been here utilized, it is apparent that the American code could be similarly translated by the introduction of a space key, which would only tend to operate the selector and not operate the horizontal releasing bars.

The details of construction are so susceptible to variations that I do not wish to limit myself to the precise construction shown herein, but rather to avail myself of any modifications that may properly fall within the scope of the invention.

40 Having thus described my invention, what I claim as new and desire to secure by Letters Patent is:

1. In a telegraphic translator, the combination of two or more responsive character keys adapted to operate selective mechanism, type bars released by said character keys through the selective mechanism, a carrier adapted to receive and move the released type bars, printing mechanism adapted to receive an impression from the selected type bar when moved by the carrier and a paper strip to record the impression; in the manner set forth and for the purpose described.

55 2. In a telegraphic translator, the combination of two or more responsive character keys, a movable selective device, a plurality of releasing bars, type bars removably secured to the releasing bars, a carrier adapted to receive the released type bars and convey them to a printing device, a strip of paper rotated intermittently by the carrier bar, an ink-bearing fabric adapted to be interposed between the paper strip and the selected type bar and means for intermittently rotating

the ink-bearing fabric operated by the carrier bar; in the manner set forth and for the purpose set forth.

3. In a telegraphic translator, the combination of one or more vertically disposed character keys, rigidly secured to horizontally disposed angle-bars, links pivotally secured to one end of the horizontally disposed angle bars, geared pinions, a pawl-carrying arm rotatably mounted on the axis 70 of the geared pinions and pivotally connected to the lower end of the link, a horizontally disposed bar substantially rectangular in cross section, on which is mounted a hollow sleeve having a toothed rack on its 80 upper surface and adapted to engage and be operated by the geared pinions, a spring on the horizontally disposed bar adapted to return the hollow sleeve to its normal position, one or more vertically disposed members 85 mounted on the hollow sleeve, springs to retain said members in their extreme upward position, bell crank levers pivotally secured to a horizontally disposed rod and retained in a certain relative position to the 90 vertically disposed members and adapted to be operated by the said members; a plurality of releasing bars extending the length of the case and having notches in one edge bearing a certain relative position to hooks 95 mounted on the upper edge of type bars extending laterally under the releasing bars, said releasing bars being adapted to be operated by the bell-crank levers by means of projections on the upper face of the bars, 100 said bell-crank levers coming in contact with the said pins at the proper time, a type face on one end of each of the type-bars, a frusto-pyramidal head secured to the type, a movable, horizontally disposed carrier bar 105 having suitable recesses for the reception of the frusto-pyramidal heads of the type, and a paper strip to receive an impression from the type, in the manner described and for the purpose set forth.

4. In a telegraphic translator, the combination of one or more vertically disposed character keys rigidly secured to horizontally disposed angle-bars, links pivotally secured to the end of the horizontally disposed angle-bars, the other end of the links being pivotally secured to a pawl-carrying arm rotatably mounted on the axes of geared pinions, a horizontally disposed bar, substantially rectangular in cross section, on which 110 is mounted a hollow sleeve having a toothed rack on its upper surface and adapted to engage and be operated by the geared pinion, a spring on the horizontally disposed bar adapted to return the hollow sleeve to 115 its normal position, one or more vertically disposed members mounted on the hollow sleeve and retained in their extreme upward position by means of springs, bell-crank levers pivotally secured to a horizontally dis- 120 125 130

posed rod and retained in a certain relative position to the vertically disposed members and adapted to be operated by said members, a plurality of releasing bars extending the length of the case and having notches in one edge, type bars extending transversely under the releasing bars and having hooks to engage certain of the notches in the releasing bars, said releasing bars being adapted to be operated by the bell-crank levers by means of small pins on the upper face of the bars, said bell crank levers coming in contact with the said pins at the proper time, a type face on one end of each of the type bars, a frusto-pyramidal head secured to the type, a movable, horizontally disposed carrier bar having suitable recesses for the reception of the frusto-pyramidal heads of the type bars, a paper strip, a circular absorbent disk adapted to retain the ink, a pawl and ratchet operated by the movement of the carrier bar, said pawl and

ratchet in turn operating two feed rollers of absorbent material and containing ink, said feed rollers engaging the circular inking disk 25 for the purpose of keeping it supplied with ink and to cause it to rotate partially with each movement of the carrier bar, a second set of feed rollers adapted to be likewise operated by each movement of the carrier bar by 30 means of a pawl and ratchet, said rollers engaging a narrow strip of paper and causing the same to travel a pre-determined distance at each movement of the carrier bar; in the manner described and for the purpose set 35 forth.

In witness whereof I have hereunto affixed my signature, in the presence of two subscribing witnesses, this 7th day of April A. D. 1910.

ADOLPH OTTO URBAN.
